UNITED STATES PATENT OFFICE

106,189

DESIGN FOR A COMBINED COCKTAIL SERVER, TRAY, AND GLASSES THEREFOR

Horace A. Fuld, New York, N. Y.

Application August 31, 1937, Serial No. 71,394

Term of patent 3½ years

To all whom it may concern:

Be it known that I, Horace A. Fuld, a citizen of the United States of America, residing in New York city, in the Borough of Manhattan, county and State of New York, have invented a new, original, and ornamental Design for a Combined Cocktail Server, Tray, and Glasses Therefor, of which the following is a specification, reference being had to the accompanying drawing, forming part thereof, wherein,

Figure 4 is an elevational view of the tray and glasses of the server, particularly illustrating the various lengths of the glasses.

I claim:

The ornamental design for a combined cocktail server, tray, and glasses therefor substantially as shown, and described.

HORACE A. FULD.
